WALL CONSTRUCTION

Frederick M. Venzie, Philadelphia, Pa., assignor
to National Gypsum Company, Buffalo, N. Y.,
a corporation of Delaware

Application April 24, 1934, Serial No. 722,056

12 Claims.

(Cl. 72—46)

My invention relates to building construction and, more particularly, to a novel interior partition wall and plaster block for use therein, and, in part, comprises a continuation of my co-pending application bearing Serial No. 708,586, filed January 27, 1934.

Similarly to the above referred to application the present invention contemplates a partition which may be constructed of blocks having finished surfaces on both sides, and the use, after erection of the partition, of additional means for maintaining adjacent units in fixed relationship one with the others, and for providing a smooth finished surface. In accordance with my present invention the blocks may be provided with grooves upon two opposite edges within which, when they are erected to form a partition, dowels may be positioned; the grooves and dowels being so sized that the dowels space apart vertically positioned units while maintaining them, as well as horizontally positioned units, in a predetermined relationship with one another.

A primary object of my invention is to provide a novel partition wall which while maintaining all of the strength of the prior art walls, may be erected without the laying of courses of mortar as the wall is erected and hence, which can be built with greater speed and more economically than the walls heretofore known.

Another primary object of my invention is to provide a novel plaster block adapted to be used in a wall construction by the use of which, in combination with dowels, the blocks may not only be spaced apart but the composite structure made stronger than a similar wall made of blocks of the usual shape.

A more specific object of my invention is to provide a novel partition wall which may be erected from units having a finished plaster surface.

A further specific object of my invention is to provide a novel partition composed of plaster blocks together with means for maintaining the edges of adjacent blocks in alignment both vertically and horizontally.

Another specific object of my invention is to provide a novel partition wall composed of units having a finished surface together with means for spacing apart said units to allow the introduction therebetween, after the units are erected, of a cementitious binder.

More specific objects of my invention reside in the results attained by eliminating from the construction job the need for applying a bond coat of mortar, plaster coat or coats. These include

greater speed of erection, greater cleanliness, and the elimination of the time lost waiting for the mortar to dry.

Other objects of my invention will be apparent from the following specification, claims, and from the drawings in which:

Fig. 1 is a side elevation of a partition wall embodying my invention;

Fig. 2 is a horizontal sectional view through a portion of the wall shown in Fig. 1;

Fig. 3 is a vertical section taken on the line 3—3 of Fig. 2;

Fig. 4 is a plan view in detail of a clip embodied in my invention;

Fig. 5 is an end elevation of the clip shown in Fig. 4;

Fig. 6 is a vertical sectional view taken on the line 6—6 of Fig. 4;

Fig. 7 is a side elevation in detail of one portion of the clip shown in Figs. 4 to 6;

Fig. 8 is a side elevation with portions broken away of a wall embodying a modified form of my invention;

Fig. 9 is a vertical sectional view through the wall shown in Fig. 8;

Fig. 10 is a vertical section, on an enlarged scale, through the wall shown in Fig. 9;

Fig. 11 is a detailed plan view of one edge of a block used in either embodiment of the wall; and

Fig. 12 is a detailed perspective view of such a block.

Referring now particularly to Figs. 1, 11, and 12, a wall embodying my invention is composed of a multiplicity of blocks 15 preferably of greater length than breadth formed of any well known and suitable material such as may have either fire-proof or sound-proof characteristics. Such a block may be rectangular in shape and may be surfaced with finishing coats 16 of plaster on its opposite major faces.

Preferably the block may be formed with longitudinal bores 17 therethrough for the purpose not only of lightening its weight but also of permitting the passage of pipes and conduits of various types.

Upon the longitudinal edges 15a of the block may be formed three grooves, the outer two being designated 18 and the central one 19. All of the grooves may be formed in the block by the use of a milling or other similar machine after the plaster coats have hardened thereon, since, while it is practicable to make the plastered blocks of uniform thickness and with parallel surfaces, it is an expensive and lengthy process to make each finish plaster coat of exactly the same

thickness at all points on both faces of the block, and formation of the grooves prior to the application of the plaster finish to the block would in the finished block cause these grooves to be spaced unequally from the finished surfaces and hence, when erected, the faces of adjacent blocks would not be in alignment. This method of forming the grooves permits the spacing thereof a predetermined distance from the finished face of the blocks. In cross section the grooves 18, 19 define an arc less than a semi-circle so that when the blocks are erected two matching edges will contain bores which are non-circular and which, upon the insertion of dowels of the same diameter as the circle of which the groove is an arc, the edge of the block will be spaced apart.

The two lateral edges of the block, here considered as vertical edges 15b, may be formed with a groove 20 therein for purposes hereinafter described, and this groove may be formed in the block at the time it is molded, as its exact dimensions are immaterial.

The embodiment of my invention shown in Figs. 1 to 6 inclusive, comprises a wall constructed of the blocks 15, the blocks being so positioned that the edges of adjacent blocks lie in a straight line. After the bottom block in each tier is positioned a channel iron 25 is suitably connected to a floor and ceiling in such a position that it lies within the groove 17 in the block. An adjacent block 15 in the lower row is positioned with its vertical edge 15b a short distance from the vertical edge of and adjacent the first block, and two dowels 26 of the same diameter as the grooves and formed of tubing or pipe as shown or of wood are inserted in the outer grooves 18 of the blocks so that the dowels pass across the crevice 42 between the two blocks and prevent movement of the blocks relative to each other out of a vertical plane. The grooves 18 are so sized relative to the outer diameter of the tubing that while the groove is cut on a circle having the same diameter as the outer diameter of the tubing, it is less than a semi-circle and hence when other blocks are placed above the tubing they, having similar sized grooves, are spaced apart by the tubing while at the same time being maintained in position relative to each other.

Prior to the erection of the second row of blocks, vertically considered, a clip indicated at 21 is passed around each of the channels 25. The clip 21 is composed of two U-shaped elements 28 and 29. Upon one leg of the element 28 is a vertical flange 30 to which is welded or otherwise connected the nut 31. A corresponding leg, on the element 29, carries a similar flange 32 with an opening 33 therein, the opening 33 being so positioned that when the clip is in assembled position it permits the passage therethrough of a rod 40 having a threaded end fitting the nut 31. The opposite leg of each of the U-shaped elements 28 and 29 is bent over upon the corresponding element as indicated in Figs. 4 and 5 to form a telescoping joint and each of these legs is formed with a hole 35 therein through which passes the opposite end 40a of the rod 40 which end is bent at a right angle to the normal line of the rod. This construction permits the parting of the clip into two separate units which may be passed around the channel 25 and will be maintained in place thereabout by the passage through the hole 35 of the end 40a of the rod 40.

With a clip positioned about two adjacent channels a rod 40 may be inserted and a turn buckle 41, provided intermediate the ends of the

rod, may be tightened to place the rod 40 under tension and tie together the adjacent channels 25, it being understood that the rod 40 and turn buckle 41 lie within the central groove 19 in the block 15. After the wall is completely erected the crevices 42 between adjacent blocks 15 may be filled by any suitable cementitious binder 14 preferably having substantially the same texture as the plaster finish on the block, this binder acting as a means for increasing the rigidity of the wall 10 as well as providing it with a smooth finish surface.

In the embodiment of my invention shown in Figs. 8 to 10 inclusive, and illustrating a construction in which the blocks are erected with their vertical joints in staggered relationship, the lower row of blocks is mounted with the blocks spaced apart slightly in any suitable fashion as for instance on a nailing strip 50 to which is connected semi-circular dowels 51 fitting the grooves 18, which construction may as well be indicative of the manner in which the lower blocks in the first described embodiment of my invention are erected. Optionally the nailing strip 50 may be milled and full rounds used. When the lower row 25 of blocks is erected bond 53 is inserted in the middle groove 19, this bond extending preferably the full length of the wall, and additionally the dowels 16 are inserted as in the first embodiment of my invention. This process is continued until 30 the uppermost row of blocks is reached, at which time as each block is erected a channel iron 54 is secured in the ceiling 55 and nails 56 are driven through openings therein into the end of a block 15, thus preventing movement of the block and wall out of a vertical plane. This wall is similarly finished by the insertion in the spaces 42 of the cementitious compound 14.

From the foregoing description it will be apparent that I have provided a partition wall which 40 not only eliminates the need of applying a finishing coat of plaster at the time it is erected but which also, while as strong as the other partition walls, is more quickly erected.

While the above described construction of a 45 partition of blocks having a plaster finish has numerous advantages and is often to be preferred, many advantages, particularly that of speed in erection may be retained if the blocks are not finished prior to erection but are erected in their 50 rough state in accordance with either of the described embodiments of my invention. When this is done the application of the finish plaster coat fills the crevices 42 and bonds the blocks together. 55

Various modifications may be made in the above described embodiments of my invention without departing from the spirit and scope thereof, as set forth in the following claims.

I claim as my invention:

1. An interior partition wall comprising a multiplicity of blocks having a finished plaster surface on their major surfaces; grooves on two opposite edges of said block; and means within said grooves for maintaining adjacent blocks, both horizontally and vertically considered, in predetermined relationship, said means spacing said blocks vertically.

2. An interior partition wall comprising a multiplicity of blocks having a finished plaster surface on their major surfaces; grooves on two opposite edges of said block; means within said grooves for maintaining adjacent blocks, both horizontally and vertically considered, in a predetermined relationship, said means spacing said 75

- blocks vertically, and means filling the space between said blocks.
3. An interior partition wall comprising a multiplicity of blocks having a finished plaster surface on their major surfaces; grooves on two opposite edges of said block; and means within said grooves for maintaining adjacent blocks, both horizontally and vertically considered, in a predetermined relationship.
- 10 4. An interior partition wall comprising a multiplicity of blocks having a finished plaster surface on their major surfaces; grooves on two opposite edges of said block; means within said grooves for maintaining adjacent blocks, both horizontally and vertically considered, in a predetermined relationship, said means spacing said blocks vertically, and other means for maintaining said blocks in a vertical plane.
- 15 5. An interior partition wall comprising a multiplicity of blocks; grooves on two opposite edges of each said block; and means, movable except for said blocks, within and in contact with said grooves for maintaining adjacent blocks, horizontally considered, in a predetermined relationship.
- 20 6. An interior partition wall comprising a multiplicity of blocks, a plaster finish on said blocks, three parallel grooves on a pair of opposite edges of each block, a vertical crevice between horizontally adjacent blocks, dowels lying within the outermost of said grooves and passing through said vertical crevice, said dowels having the same outer diameter as the diameter of said grooves but said grooves being less than a semi-circle in periphery whereby adjacent blocks, vertically considered, are spaced apart and at the same time are prevented from movement about any vertical axis, means for maintaining the wall in a vertical plane, and means for filling the crevices between adjacent blocks and cementing adjacent blocks together.
- 25 7. An interior partition wall comprising a multiplicity of blocks, three parallel grooves on a pair of opposite edges of each block, a vertical crevice between horizontally adjacent blocks, dowels lying within all of said grooves and passing through said vertical crevice, two of said dowels passing through one crevice only and the other of said dowels passing through more than one crevice, said dowels having the same outer diameter as the diameter of said grooves but said grooves being less than a semi-circle in periphery whereby adjacent blocks, vertically considered, are spaced apart and at the same time are prevented from movement about any vertical axis, and means for filling the crevices between adjacent blocks and cementing adjacent blocks together.
- 30 8. An interior partition wall comprising a multiplicity of blocks; three parallel grooves on a pair of opposite edges of each block, a vertical crevice between horizontally adjacent blocks, dowels lying within the outermost of said grooves and passing through said vertical crevice, means connecting to the floor and ceiling for maintaining the wall in a vertical plane; means lying in the third of said grooves connecting said last named means; and means for filling the crevices between adjacent blocks and cementing adjacent blocks together.
- 35 9. An interior partition wall comprising a multiplicity of blocks arranged in adjacent tiers, the vertical and horizontal edges of the blocks being arranged in alignment with the corresponding edges of adjacent blocks, depressions in the adjacent edges of vertically spaced blocks, said depressions being adjacent the ends of said edges, and a member within said depressions extending over the vertical crevice between blocks.
- 40 10. An interior partition wall comprising a multiplicity of blocks, a plaster finish on said blocks, three parallel grooves on a pair of opposite edges of each block, said wall being erected with vertical crevices between horizontally adjacent blocks, dowels lying within the outermost of said grooves and passing through said vertical crevice, and means comprising a channel iron lying within said vertical crevice and between said dowels for maintaining the wall in a vertical plane.
- 45 11. An interior partition wall comprising a multiplicity of blocks, a groove on a pair of opposite edges of each block, said wall being erected with vertical crevices between horizontally adjacent blocks, a dowel lying within said groove and passing through said vertical crevice, means for maintaining the wall in a vertical plane, and means for filling the crevices between adjacent blocks and cementing adjacent blocks together.
- 50 12. An interior partition wall comprising a multiplicity of blocks with depressions in their horizontal edges, said depressions being complementally shaped and bonding means fitting said depressions but being larger than the complemental pair and extending over the vertical joint between horizontally adjacent blocks whereby vertically adjacent blocks are spaced apart and horizontally and vertically adjacent blocks are positioned with respect to one another.

FREDERICK M. VENZIE. 55
